US0D1047636S

(12) **United States Design Patent** (10) **Patent No.:** **US D1,047,636 S**
(45) **Date of Patent:** **** Oct. 22, 2024**

(54) **SAW BLADE**

(71) Applicant: **DePuy Synthes Products, Inc.**,
Raynham, MA (US)

(72) Inventors: **Patrick Uhri**, Reigoldswil (CH); **Stefan Gisler**, Wallbach (CH); **Rolf Schlienger**, Rheinfelden (CH); **Markus Hermann**, Laupersdorf (CH); **Matthias Singeisen**, Itingen (CH); **David Narducci**, Jupiter, FL (US)

(73) Assignee: **DePuy Synthes Products, Inc.**,
Raynham, MA (US)

(**) Term: **15 Years**

(21) Appl. No.: **29/872,523**

(22) Filed: **Mar. 14, 2023**

(51) LOC (14) Cl. **08-03**

(52) U.S. Cl.

(57) **CLAIM**

The ornamental design for a saw blade, as shown and described.

DESCRIPTION

FIG. 1 is a top front perspective view of a saw blade showing our new design;

FIG. 2 is a bottom back perspective view of the saw blade of FIG. 1;

FIG. 3 is a top view of the saw blade of FIG. 1;

FIG. 4 is a bottom view of the saw blade of FIG. 1;

FIG. 5 is a right view of the saw blade of FIG. 1, the left view being a mirror image thereof;

FIG. 6 is a front view of the saw blade of FIG. 1; and,
FIG. 7 is a back view of the saw blade of FIG. 1.

The dash-dash broken lines illustrate portions of the saw blade that form no part of the claimed design.

The dash-dot lines illustrate boundary lines of the saw blade that form no part of the claimed design.

1 Claim, 5 Drawing Sheets
